OPEN END WRENCH HAVING A BALL HANDLE GRIP

Benard C. Anderson, Kenosha, Wis.

Application March 7, 1951, Serial No. 14,411

Term of patent 14 years

(CL. D54—16)

To all whom it may concern:

Be it known that I, Benard C. Anderson, a citizen of the United States, residing at 3103 14th Avenue, in the county of Kenosha and the State of Wisconsin, have invented a new, original, and ornamental Design for Open End Wrench Having a Ball Handle Grip, of which the following is a specification, reference being had to the accompanying drawing, forming part thereof.

Figure I is a plan view of an open end wrench having a ball handle grip, showing my new design.

Figure II is a top view thereof.

Figure III is an end view thereof.

Figure IV is a cross-sectional view of Figure I taken on line A—A.

I claim:

The ornamental design for an open end wrench having a ball handle grip, as shown.

BENARD C. ANDERSON.
